CLAIM

The ornamental design for a gene amplification equipment, as shown and described.

DESCRIPTION

FIG. 1 is a top, front, right perspective view of a gene amplification equipment showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged cross-sectional view taken along line 8-8 in FIG. 2 for clarity of disclosure.

The broken lines in the drawings illustrate portions of the gene amplification equipment which form no part of the claimed design.
